AIR SUPPLY DEVICE

Franz J. Kurth, New York, N. Y., assignor to
Anemostat Corporation of America, a corpora-
tion of Delaware

Application November 23, 1937, Serial No. 176,070

8 Claims. (Cl. 98—40)

This invention relates to the art of ventilation, and has particular reference to improvements in air supply and distributing devices of the type comprising a plurality of successively larger, hollow flaring members disposed relatively to each other to provide a plurality of flaring passageways therebetween, whereby air flowing through the device into a room or other enclosure is effectively diffused.

Generally speaking, the object of the present invention is to provide an air distributing device of the character stated embodying a construction whereby differences in the flow of air through different transverse portions or zones of the individual passageways, and through different transverse portions or zones of the device as a whole, are obtained, to the end of providing for most suitable diffusion of the air in particular instances, as, for example, where it may be desired to have a greater or a lesser amount of air flow from the device in one or more directions than in one or more other directions.

More particularly, the object of the invention is to provide an air distributing device of the character stated embodying a construction whereby air flowing forwardly through the device produces an air suction effect in portions of certain of the passageways, thereby to obtain a mixing, within the device and in the immediate vicinity of the same, of air supplied by the device with air into which the supplied air is delivered, and whereby differences in the amount of air flowing forwardly and rearwardly through different portions or zones of the individual passageways, transversely thereof as viewed from the front of the device, and through different portions or zones of the device as a whole, transversely thereof as viewed from the front of the device, are obtained, to the end of providing for most suitable diffusion of the air in particular installations as aforesaid.

One special utility of the features comprising the invention is in connection with air distributing devices of the character stated which are associated with side wall air outlets. In that connection an important object of the invention is to provide an air distributing device of the character stated, especially for use with a side wall outlet of an air supply conduit disposed at an elevation above the average person's head, embodying a construction whereby little or no air flows directly downwardly and forwardly from the device, but, on the contrary, there is mainly a recirculation flow of air, and a mixing of the supplied air with the air into

which the supplied air is delivered, directly below and directly forwardly of the device, a progressively decreasing recirculation flow and mixing of air laterally and upwardly from the medial portion toward the side portions of the device, primarily a forward and lateral or fan-like outward flow of air from the top portion of the device horizontally, and a gradual blending of the respective flows of air with each other, thus practically to eliminate the possibility of a person standing beneath, or directly forwardly, or in any position relative to the device, experiencing a sensation of draft.

With the foregoing and other objects in view, which will become more fully apparent as the nature of the invention is better understood, the same consists in an air distributing device of the character stated embodying the novel features of construction as will be hereinafter more fully described, illustrated in the accompanying drawings and defined in the appended claims.

In the accompanying drawings, wherein like characters of reference denote corresponding parts in the different views:

Figure 1 is a central, vertical section through an air distributing device especially designed for use with a side wall outlet of an air supply conduit and embodying the features of the present invention.

Figure 2 is a horizontal section through the device shown in Fig. 1, the section being taken directly below the top cover plate of the device.

Figure 3 is a perspective view of the device shown in Figs. 1 and 2 as viewed from the front and to one side thereof.

Figure 4 is a front elevation of the device; and

Figure 5 is a perspective view of the device as viewed from the front and below the same, the angle of view being substantially as indicated by the arrow designated as V in Fig. 1 of the drawings.

Referring to the drawings in detail, it will be observed that the device is of a known general type comprising a plurality of successively larger, open-ended hollow flaring members all having their smaller ends facing the rear or air inlet end of the device and all disposed in axial alignment, or substantially in axial alignment with each other and in spaced apart relationship to provide therebetween a plurality of flaring passageways for flow of air through the device.

The device, as viewed from its front, may be 55. of circular, elliptical, semi-circular or other

suitable shape, depending upon whether it is to be used with a ceiling or a side wall outlet of an air supply conduit and depending, also, upon particular conditions encountered and the particular air diffusion desired in any particular installation. In the present instance the device is illustrated as being of flat-top semi-circular shape as viewed from the front and as embodying a construction especially adapting it for use with a side wall outlet of an air supply conduit disposed at an elevation above the average person's head.

While the device may be comprised by different numbers of flaring members, a practical number of such members is five, and this is the number of said members illustrated in the present instance. These members, beginning with the innermost or smaller member and reading outwardly, are designated as 1, 2, 3, 4 and 5, respectively, and, as shown, they are hollow, open at their ends, axially aligned, disposed with their rear or smaller ends facing the rear or air inlet end of the device, of progressively increasing flare, respectively, reading outwardly, and disposed in spaced apart relationship whereby there are provided between them flaring passageways open at their rear and outer ends and designated as b, c, d and e, respectively.

Behind the larger or outermost flaring member 5 and spaced rearwardly therefrom is a flat or a substantially flat plate 6 which is vertically or substantially vertically disposed and which cooperates with said larger or outermost flaring member 5 to provide an outermost flaring passageway f. On the other hand, at the top of the device is a cover plate 7 which is horizontally or substantially horizontally disposed and closes the tops of the flaring passageways b, c, d, e and f and cooperates with the smaller or innermost flaring member 1 to provide an innermost flaring passageway a. In the plate 6 is an opening 8 for flow of air into the device.

Preferably, the forward ends of the flaring members 1, 2, 3, 4 and 5 are successively stepped rearwardly, relative to each other. As a consequence, the device as an entirety and the plate 7 are of substantially semi-circular shape as viewed in plan.

The device may have a neck of semi-circular or any other suitable cross-sectional shape extending rearwardly from the plate 6 for connecting the device with a side wall outlet 9 of an air supply conduit 10, or the device may be operatively mounted with respect to a side wall outlet such as that designated as 9 in any other suitable manner.

Referring now particularly to the rear or smaller ends of the flaring members 1, 2, 3, 4 and 5, it will be observed that the same have a peculiar and novel relationship to each other whereby the purposes of the invention are attained. First, it will be observed by reference to Figs. 1 and 4 that the lowermost portion of the smaller end of the member 5 is disposed in substantially the same horizontal plane as the lowermost portion of the opening 8 in the plate 6 and that, from its lowermost portion the said smaller end of said member 5, as it extends upwardly to either side of the medial, vertical plane of the device, extends also laterally inwardly relative to prolongations of the side portions of the opening 8 as indicated at 11. In other words, the upper portions of the smaller end of the member 5, as viewed from the front of the device, are disposed in overlapping relationship

to the opening 8 and these overlapping portions progressively decrease in area toward the bottom of the smaller end of said member which, as aforesaid, is aligned, or substantially aligned, with the bottom of the opening 8. Accordingly, air is free to flow from the outlet 9 across the lower portion of the smaller end of the passageway f and is not deflected into the bottom portion of said passageway; whereas, toward the top of said passageway f at each side of the device the portions 11 of the smaller end of said member 5 intercept and direct air laterally outwardly through said passageway f in progressively increasing amounts upwardly.

15 The smaller end of the member 4 bears the same general relationship to the smaller end of the member 5 as the smaller end of the latter member bears to the opening 8, with the difference, however, that the lowermost portion of the smaller end of the member 4 is disposed slightly above the lowermost portion of the smaller end of the member 5, as clearly illustrated in Figs. 1 and 4. As a result, a small amount of the supplied air is intercepted by the lowermost portion of the smaller end of the member 4 and is deflected into the lowermost portion of the passageway e, this air flowing only through the forward part of the lowermost portion of said passageway e, as indicated by the arrows x in Figs. 1 and 5, and there being a rearward flow of air through the rear part of the lowermost portion of said passageway e, as indicated by the arrows y in Figs. 1 and 5, due to the suction effect produced by the main body of the supplied air flowing across the lowermost portion of the smaller end of the member 4. Upwardly from the medial portion of the passageway e toward either side of the device there is also both a forward and a rearward flow of air through said passageway and, consequently, a mixing within and beyond said passageway of the air flowing forwardly therethrough and therefrom with the air flowing rearwardly thereto and therethrough, but, as is apparent, the forward flow of air progressively increases and the rearward flow of air progressively decreases from the bottom of said passageway upwardly at each side thereof due to the progressively increasing overlapping relationship upwardly to either side of the device of the smaller end portion of the member 4 with respect to the smaller end portion of the member 5.

45 The smaller end of the member 3 bears the same general relationship to the smaller end of the member 4 as the smaller end of the latter member bears to the smaller end of the member 5. However, the lowermost portion of the smaller end of the member 3 is disposed higher above the lowermost portion of the smaller end of the member 4 than the lowermost portion of the smaller end of the member 4 is disposed above the lowermost portion of the smaller end of the member 5. Consequently, while there is both a forward and a rearward flow of air through the lowermost portion of the passageway d, as indicated by the arrows x' and y' in Figs. 1 and 5, the proportions of the air flowing forwardly and rearwardly through the lowermost portion of said passageway d are, respectively, greater and lesser as compared with the proportions of the air flowing forwardly and rearwardly through the lowermost portion of the passageway e. Upwardly from the medial portion of the passageway d toward either side of the device there is also both a forward and a rearward flow

of air through said passageway and, consequently, a mixing within and beyond said passageway of the air flowing forwardly therethrough and therebeyond with the air flowing rearwardly thereto and therethrough, but, as is apparent, the forward flow of air progressively increases and the rearward flow of air progressively decreases from the bottom of said passageway upwardly toward each side of the device due to the progressively increasing overlapping relationship upwardly of the smaller end of the member 3 with respect to the smaller end of the member 4.

The smaller end of the member 2 bears the same general relationship to the smaller end of the member 3 as the smaller end of the latter member bears to the smaller end of the member 4, and the resultant flow of air through the passageway c is generally the same as in the passageway d, the only essential difference being that the lower portion of the smaller end of the member 2 is disposed somewhat higher above the lower portion of the smaller end of the member 3 than the lower portion of the smaller end of the latter member is disposed above the lower portion of the smaller end of the member 4, with the result that, as compared with the flow of air in the lower portion of the passageway d, the forward flow of air through the lower portion of the passageway c is somewhat greater and the rearward flow of air through said passageway is somewhat less. Upwardly from the bottom of the passageway c toward either side of the device there is both a rearward and a forward flow of air through said passageways and, consequently, a mixing within and beyond said passageway of the air flowing forwardly therethrough and therefrom with the air flowing rearwardly thereto and therethrough, due to the progressively increasing overlapping relationship upwardly to either side of the device of the smaller end of the member 2 with respect to the smaller end of the member 3, but, as compared with the forward and rearward flows of air through the sides of the passageways d, the corresponding air flows in the corresponding portions of the passageway c are greater and lesser, respectively, due to the generally more wide open nature of the smaller end of the passageway c.

The smaller end of the member 1 bears generally the same relationship to the smaller end of the member 2 as the smaller end of the latter member bears to the smaller end of the member 3, and the resultant flows of air through the passageway b are therefore generally the same as through the passageway c, except that, proportionately, more air flows forwardly and a lesser amount of air flows rearwardly through said passageway b than through the passageway c.

Through the passageway a there is primarily a flow of air forwardly and laterally and slightly downwardly from the device, due to the top plate 1 and to the lack of anything to interfere with direct flow of air from the outlet 9 through said passageway a. However, due to the flare of the member 1, a slight rearward or aspirating flow of air occurs in the passageway a, as indicated by the arrows in Figs. 1 and 5 of the drawings.

From the foregoing it will be apparent that, within a medial zone transversely of the device, as the latter is viewed from the front, the air flow is primarily forwardly at the top of the device, primarily rearwardly at the bottom of the device and gradually lesser rearwardly and gradually greater forwardly from the bottom toward

the top of the device. Also, it will be apparent that, at each side and toward the top of the device, the air flow is primarily forwardly; that, at each side and toward the aforesaid medial zone of the device, the air flow is primarily rearwardly but not as pronounced as in the said medial zone of the device; that, at each side of the device, the forward flow of air progressively increases and the rearward flow of air progressively decreases toward the top of the device, and that there is a gradual blending of the various flows with each other as set forth. Accordingly, assuming that the device is associated with a side wall outlet of an air supply conduit located above the average person's head, it is apparent that the device practically eliminates the possibility of a person standing beneath, or directly forwardly, or to either side of the device, or in fact in any position relative thereto, experiencing any sensation of draft. At the same time, the device provides for the supply of air to accomplish effective ventilation.

The respective members comprising the device may, of course, be secured in assembly with each other in any suitable manner. As illustrated in the present instance they are in part secured in assembly by the top plate 1 and in part by a rod 12.

While only a single specific embodiment of the invention has been illustrated and described, it is apparent that the features comprising the invention may readily be embodied in other air diffusing devices of various other specifically different constructions and shapes and in such manner as to cause desired amounts of air to flow forwardly from and rearwardly into the device in any desired transverse zone or zones thereof, all within the spirit and scope of the invention as defined in the appended claims.

40 I claim:

1. An air outlet device of substantially U-shape in end elevation having a flat side and comprising a series of successively smaller, open-ended, hollow, flaring members of substantially U-shape in end elevation and spaced successively inwardly of one another with their smaller ends disposed at the rear or air inlet end of the device to provide therebetween a series of flaring passageways of substantially U-shape in end elevation, and means closing said passageways at the flat side of the device, said members having the medial portions of their rear edges disposed inwardly of the medial portions of the rear edges of the next larger members, respectively, and at least one 55 of said members having the side portions of its rear edge disposed farther inwardly from the side portions of the rear edge of the next larger member than its medial portion is disposed inwardly of the medial rear edge portion of the said next larger member, whereby a lesser amount of supplied air flows through the medial portion than through the side portions of the passageway between said members.

2. An air outlet device of substantially U-shape in end elevation having a flat side and comprising a series of successively smaller, open-ended, hollow, flaring members of substantially U-shape in end elevation and spaced successively inwardly of one another with their smaller ends disposed at the rear or air inlet end of the device to provide therebetween a series of flaring passageways of substantially U-shape in end elevation, and means closing said passageways at the flat side of the device, each of said members having the medial portion of its rear edge disposed inwardly

of the medial portion of the rear edge of the next larger member to deflect supplied air through the medial portions of the passageways between said members, at least one of said members further having the side portions of its rear edge disposed greater distances inwardly from the side portions of the next larger member than its medial rear edge portion is disposed inwardly of the medial rear edge portion of the said next larger member so that more supplied air flows through the side portions than through the medial portion of the passageway between said members, the medial portion of the rear edge of at least one of said members being disposed a greater distance inwardly of the medial portion of the next larger member than the medial portion of the rear edge of a larger of said members is disposed inwardly of the rear edge of the next larger member.

3. An air outlet device as set forth in claim 2 in which the said inward disposition of the side portions of the rear edge of the said at least one of said members progressively decreases toward the medial portion of said member.

4. An air outlet device as set forth in claim 2 in which the said inward disposition of the medial portion of the rear edge of the said at least one of said members progressively increases toward the side portions of the rear edge of said member.

5. An air outlet device as set forth in claim 2 in which the medial portions of the rear edges of the successively smaller members are disposed progressively greater distances inwardly of the medial portions of the rear edges of the next larger members, respectively.

6. An air outlet device as set forth in claim 2 in which the side portions of the rear edges of the successively smaller members are disposed progressively greater distances inwardly of the side portions of the rear edges of the next larger members, respectively.

7. An air outlet device of substantially U-shape in end elevation having a flat side and comprising a series of successively smaller, open-ended, hollow, flaring members of substantially U-shape in end elevation and spaced successively inwardly of one another with their smaller ends disposed at the rear or air inlet end of the device to

provide therebetween a series of flaring passageways of substantially U-shape in end elevation, and means closing said passageways at the flat side of the device, a rearmost member spaced 5 rearwardly from the largest flaring member to provide therebetween a rearmost flaring passageway, said rearmost member having an opening for the admission of supplied air to the device, the medial portion of the rear edge of the largest flaring member being disposed at least as far outwardly as the corresponding portion of the opening in said rearmost member, whereby supplied air is permitted to flow across the mouth of the medial portion of the rearmost passageway and to produce aspiration in the said medial portion of said rearmost passageway, the side portions of said largest flaring member being disposed inwardly of the side portions of said opening whereby supplied air is deflected through the side portions of said rearmost passageway.

8. An air diffusing device of substantially semi-circular shape in front elevation having a substantially flat side and comprising a series of successively smaller, hollow, flaring members of substantially semi-circular shape in front elevation spaced successively inwardly of one another to provide a plurality of flaring passageways therebetween, a plate cooperating with said members to close said passageways at the flat side of the device, the smaller ends of said members being disposed rearwardly relative to the device and the rear edge portions of at least one of said members to either side of the central, vertical plane of the device being disposed inwardly with respect to forward prolongations of the rear edge portions directly therebehind of the next adjacent outwardly disposed member to deflect air, delivered forwardly through the rear end of said next adjacent outwardly disposed member, into the passageway between said members, the amount of inward disposition of the said rear edge portions of said first mentioned member with respect to forward prolongations of the rear edge portions directly therebehind of the next adjacent outwardly disposed member progressively decreasing toward the central, vertical plane of the device.

FRANZ J. KURTH.
